US0D1042226S

(12) **United States Design Patent** (10) **Patent No.:** **US D1,042,226 S**
(45) **Date of Patent:** **** Sep. 17, 2024**

(54) **ELECTRIC VEHICLE**

(71) Applicant: **Alpha Motor Corporation**, Irvine, CA (US)

(72) Inventor: **Edward Yoon Lee**, Irvine, CA (US)

(73) Assignee: **Alpha Motor Corporation**, Irving, CA (US)

(**) Term: **15 Years**

(21) Appl. No.: **29/838,840**

(22) Filed: **May 16, 2022**

(51) LOC (14) Cl. **12-08**

(52) U.S. Cl.

USPC **D12/91**

(58) **Field of Classification Search**

USPC D12/86, 88, 90-92, 164; D21/433, 434,

D21/533, 535; 296/181.1-181.5, 183.1

CPC B62D 25/00; B62D 25/06; B62D 33/00;

B62D 35/00

(57) **CLAIM**

The ornamental design for an electric vehicle, as shown and described.

DESCRIPTION

FIG. 1 is a front and left side perspective view of an electric vehicle showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 7 Drawing Sheets
